UNITED STATES PATENT OFFICE.

JOHN MADDEN, OF OVERLAND PARK, MISSOURI, ASSIGNOR TO INTERNATIONAL SHOE COMPANY, OF ST. LOUIS, MISSOURI, A CORPORATION OF DELAWARE.

SHOE SNUG.

Application filed June 21, 1928. Serial No. 287,119.

This invention relates to shoe snugs for insertion in shoes to hold the shoes expanded.

An object of the invention is to provide a shoe snug comprising a resilient member de-

signed and adapted to be inserted in a shoe with one end abutting against the inside of the rear portion of the shoe and the opposite end extending into the toe portion of the shoe and exerting pressure against the toe portion 10 of the shoe to hold the same distended and open in its natural and intended form.

Another object of the invention is to provide a device of the character mentioned having, in combination with a longitudinal resilient member, a resilient arcuate member designed and adapted to fit within the upper part of the toe portion to hold the same distended and in proper form.

Another object of the invention is to provide a device of the character mentioned designed and adapted for use in shoes of different types, it being possible to modify the longitudinal resilient member for different adaptations.

Other objects will appear from the following description, reference being made to the drawings in which

Fig. 1 is a side elevation of one form of the invention fitted within a shoe.

Fig. 2 is a plan view of the device.

Fig. 3 is a front elevation.

Fig. 4 is a side elevation of another form of the invention applied within a shoe.

Fig. 5 is a plan view of this different form 35 of the device.

Fig. 6 is a front end elevation.

The device shown in Figs. 1 to 3, inclusive, is designed and adapted for use in shoes of the type comprising high uppers or of the 40 type comprising straps passing over the insteps of the wearer. Said device includes a longitudinal resilient member which, in the embodiment shown, is a strip of resilient sheet metal having its rear lower end rolled to provide a ring 1 from which the sheet metal strip extends upwardly to form a rear abutting portion 2 continuing forwardly as a downwardly bowed portion 3, the upper forward portion of which is curved and extended down- 45 wardly and forwardly to provide a part 4 of a length to extend into the toe portion of the shoe and terminating in a rolled ring 5.

The part 4 is bent to form a depressed seat 50 designed and adapted to receive the shoe strap 55 7 of the type of shoe shown in broken lines in

Fig. 1. Or, the curved union 8 of the parts 3 and 4 may function as an abutment for the adjacent part of a shoe having a high upper portion.

When this longitudinal resilient member is 60 inserted in the shoe for which it is designed and intended the ring 1 seats upon the top of the inner sole, the curved portion 2 presses rearwardly against the inside of the heel portion of the shoe and the ring 5 abuts against 65 the inside of the toe portion of the shoe, thus tending to hold the shoe sole and the other engaged parts of the shoe in proper form.

An arcuate resilient member 9 is attached 70 to the part 4 of the longitudinal resilient member and is shaped and formed so that when the device is inserted in a shoe this arcuate resilient member holds the front portion of the shoe distended by engaging against the 75 inner side thereof near the upper edge. The ends of the member 9 are bent inwardly upon themselves, as indicated at 10.

Thus it will be seen that the device specifically illustrated in Figs. 1 to 3 is designed 80 and adapted for use in shoes having high uppers or having straps. The device may be easily inserted or removed and when in use will hold the shoes from becoming distorted and is therefore highly useful for holding 85 shoes in proper shape during shipment or display or when not in use.

The device shown in Figs. 4 to 6, inclusive, 90 comprises a longitudinal resilient member preferably in the form of a strip of sheet metal having its rear lower end rolled to provide a ring 11 from which the sheet metal strip extends upwardly to form a rear abutting portion 12 continuing forwardly as a downwardly bowed portion 13, the upper forward portion of which is curved and extended downwardly and forwardly to provide a part 14 of a length to extend into the toe portion of the shoe and terminating in a rolled ring 15.

When this longitudinal resilient member is 95 inserted in the shoe for which it is designed and intended the ring 11 seats upon the top of the inner sole, the curved portion 12 presses rearwardly against the inside of the heel portion of the shoe and the ring 15 abuts against 100 the inside of the toe portion of the shoe, thus tending to hold the shoe sole and the other engaged parts of the shoe in proper form.

An arcuate resilient member 16 is attached 105 to the part 14 of the longitudinal resilient 110

member and is shaped and formed so that when the device is inserted in a shoe this arcuate resilient member holds the front portion of the shoe distended by engaging 5 against the inner side thereof near the upper edge. The ends of the member 16 are bent inwardly upon themselves, as indicated at 17.

Thus it will be seen that the device specifically illustrated in Figs. 4 to 6 is designed 10 and adapted for use in shoes of the low or oxford type, although it may be used with a considerable degree of satisfaction in shoes of other types.

The invention may be varied as to form in 15 other respects than in those specifically shown and described and I contemplate such variations as may be deemed useful.

I do not restrict myself in these or other respects, but what I claim and desire to secure 20 by Letters Patent is:

1. A device of the character described comprising a resilient metallic strip shaped to provide a downwardly curved part at its rear end arranged to press against the inside of the 25 heel portion of a shoe, a forwardly extended downwardly curved portion, a portion extending downwardly and forwardly from the upper end of said last named curved portion having its front end arranged to press against 30 the inside of the toe of a shoe and its intermediate portion arranged to support the front of the shoe upper, an arcuate resilient member attached to said last named portion of said member and arranged to hold the shoe 35 upper distended, and a seat formed on said downwardly and forwardly extended portion adapted to receive and hold a shoe strap.

2. A device of the character described comprising a longitudinal resilient member 40 designed and adapted for insertion in a shoe in which the front and rear portions of said member abut against the inner sides of the toe and heel portions of the shoe, respectively, and an arcuate resilient member attached to 45 said longitudinal resilient member approximately midway of the ends of said arcuate member, said arcuate member being curved

approximately to the curvature of the front portion of the shoe upper in a plane nearly parallel with the upper edge of said upper 50 and having its end extending rearwardly approximately parallel with the upper edge of the shoe in which the device is mounted and pressing outwardly against the inner sides of the upper marginal portions of the shoe 55 and holding the shoe distended in its intended shape.

3. A device of the character described comprising a longitudinal resilient member designed and adapted for insertion in a shoe in 60 which the rear portion of said member abuts against the inner side of the heel portion of the shoe, and an arcuate resilient member attached to said longitudinal resilient member approximately midway of the end of said 65 arcuate member, said arcuate member being curved approximately to the curvature of the front portion of the shoe upper in a plane nearly parallel with the upper edge of said upper and having its ends extending rearwardly approximately parallel with the upper 70 edge of the shoe in which the device is mounted and pressing outwardly against the inner sides of the upper marginal portions of the shoe and holding the shoe distended in its 75 intended shape.

4. A device of the character described comprising a longitudinal resilient member designed and adapted for insertion in a shoe in 80 which the rear portion of said member abuts against the inner side of the heel portion of the shoe, a portion extending forwardly from the upper end of said curved part and having its front end extended downwardly and forwardly, a seat formed on said downwardly 85 and forwardly extended portion adapted to receive and hold a shoe strap, and an arcuate resilient member attached to said downwardly and forwardly extended portion and arranged to press outwardly against and hold 90 the intermediate portions of the shoe upper distended in the intended shape.

JOHN MADDEN.
